Primary Examiner — Abraham Bahta(74) *Attorney, Agent, or Firm* — NIXON PEABODY LLP(57) **CLAIM**

The ornamental design for a packaging container, as shown and described.

DESCRIPTION

FIG. 1 is a perspective view of a packaging container showing my new design;

FIG. 2 is a front view thereof;

FIG. 3 is a side view thereof;

FIG. 4 is a top view thereof;

FIG. 5 is a bottom view thereof; and,

FIG. 6 is a perspective view thereof, the packaging container shown in a filled state.

The broken lines are only for illustrative purpose to show environmental structure and form no part of the claimed invention.
